US00D836614S

(12) **United States Design Patent** (10) **Patent No.:** **US D836,614 S**
(45) **Date of Patent:** **** Dec. 25, 2018**

(54) **MOLDABLE EARPIECE**(71) Applicant: **Decibullz LLC**, Loveland, CO (US)(72) Inventor: **Kyle J Kirkpatrick**, Loveland, CO (US)(73) Assignee: **Decibullz LLC**, Fort Collins, CO (US)(***) Term: **15 Years**(21) Appl. No.: **29/599,445**(22) Filed: **Apr. 3, 2017****Related U.S. Application Data**

(63) Continuation of application No. 29/536,192, filed on Aug. 14, 2015, now Pat. No. Des. 783,003, which is a continuation-in-part of application No. 14/611,332, filed on Feb. 2, 2015, now Pat. No. 9,179,211, which is a continuation-in-part of application No. 13/761,947, filed on Feb. 7, 2013, now Pat. No. 9,451,353.

(57) **CLAIM**

I claim the ornamental design for a moldable earpiece, as shown and described.

DESCRIPTION

FIG. 1 is a top and right side perspective view of a moldable earpiece, embodying our new moldable earpiece design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

In the drawing, the claimed design is defined by the shaded surfaces; the broken lines depict environment that form no part of the claimed design.
